UNITED STATES PATENT OFFICE.

ARTHUR T. KATHNER, OF HOLLIDAYS COVE, WEST VIRGINIA.

CONVEYER FOR HEAT-TREATING FURNACES.

Application filed January 31, 1927. Serial No. 164,888.

This invention relates broadly to conveyers for heat treating furnaces, annealing furnaces, lehrs, and the like, and more specifically to a shaft for such conveyers.

5 The primary object of the invention is to provide a hollow shaft for conveyers of the so-called disk type employed in furnaces, lehrs and ovens wherein high temperatures are maintained, said shaft preferably being 10 made of an alloy metal which shall be especially resistant to abrasion, corrosion and oxidation.

A further object is to provide a shaft of the character referred to produced by forging, 15 rolling, drawing, or piercing, as distinguished from the usual mold casting method of making such shafts and which, therefore, requires little or no machine work to be performed thereon preparatory to 20 mounting thereon the usual conveyer wheels or disks, with the end in view to greatly reduce production costs.

A still further object is to provide a conveyer shaft which, while of relatively small 25 diameter and light weight, shall possess the requisite strength to withstand the strains imposed thereon.

Another object is to provide a shaft of the character referred to which is adapted to 30 free itself of much of the heat which is communicated thereto, expelling such heat at points wherein it is utilized in heating the furnace walls rather than wasted with the end in view to eliminate the waste of heat 35 from the lower part of the furnace.

With these and other objects in view, the invention resides in the features of construction which will hereinafter be fully described, reference being had to the accompanying drawings, in which—

40 Figure 1 is a longitudinal sectional view of a conveyer shaft constructed in accordance with the invention, the same being shown associated with a furnace or oven; 45 and—

Figure 2 is an enlarged section on line 2—2, Fig. 1.

Referring to said drawings, 1 designates a 50 hollow conveyor shaft adapted to be disposed transversely within a furnace, lehr, oven or the like, and to have its opposite ends projected outwardly through the side walls 2 of such furnace and mounted in suitable bearings, as 3. Said shaft is designed to 55 have fixed thereon within the furnace a plurality of disks, as 4, upon which the metal

to be treated is transported through the furnace.

Said shaft is made by a forging, rolling, drawing, or piercing method, as distinguished from mold casting, and is of substantially uniform diameter throughout, and, therefore, requires little or no machining to adapt it for the reception of the disks 4, 60 bearings 3, and drive gears 5. 65

The opposite ends of the shaft have the hollow or bore 6 thereof closed, as by means of plugs 7, for preventing the escape through said ends of heat imparted to the shaft; and those portions of said shaft which penetrate 70 the walls 2 of the furnace are provided with a plurality of vents 8 adapted to discharge such heat into openings 9 provided in said walls, said openings being of materially greater diameter than the shaft and having 75 the latter projected therethrough, as shown. The outer ends of said openings 9 are closed, as by a shaft-embracing collar 10, while the inner ends thereof are in open communication with the interior of the furnace. Thus, 80 heat discharged into the openings 9 through the vents 8 of the shaft and not utilized in heating the furnace walls is permitted to return to the interior of the furnace rather than discharged outside the furnace walls. 85

While the shaft may be made of steel, it is preferred that an alloy metal, which is particularly resistant to the usual ill effects of heat upon metals, be employed.

What is claimed is—

1. In a conveyer for heat-treating furnaces, a tubular shaft of substantially uniform diameter throughout, and means closing the ends of said shaft, said shaft being devoid of perforations except in the portions 95 of the ends thereof which are received by the furnace walls, the perforations of said end portions constituting vents through which heat is discharged into direct contact with the furnace walls for heating the latter. 100

2. In a conveyer for heat-treating furnaces, a hollow shaft for carrying conveyer disks, said shaft being of substantially uniform diameter throughout, and means closing the ends of said shaft, said shaft having 105 perforations only in those portions thereof which are located within the furnace walls when the shaft occupies operative position, said perforations constituting vents through which heat is discharged for heating said 110 walls.

3. The combination with a heat-treating

furnace having openings in its walls, of a tubular conveyer shaft disposed transversely within said furnace with its ends projecting outwardly through said openings, said openings having a diameter materially greater than that of said shaft, means closing the ends of said shaft, and means closing the outer ends of said openings, said shaft having therein vents through which heat is discharged from its interior into said openings for heating said walls. In testimony whereof, I affix my signature.

ARTHUR T. KATHNER.
